UNITED STATES PATENT OFFICE

2,204,317

COMBUSTION APPARATUS

Donald J. Mosshart, Springfield, Pa., assignor of
one-half to Harold F. Hildreth, Long Meadow,
Mass.

Original application April 19, 1935, Serial No.
17,162. Divided and this application Decem-
ber 7, 1936, Serial No. 114,601

13 Claims. (Cl. 110—110)

My invention relates to combustion apparatus, and more particularly to stoker-fired furnaces having means for discharging and crushing the ash; the present application being a division of 5 my copending application Serial No. 17,162, filed April 19, 1935, and patented Jan. 10, 1939, Patent No. 2,143,834.

One object of my invention is to provide apparatus of the above type which is of improved 10 construction and arrangement of parts.

A further object is to provide an improved 15 form of stoker-fired furnace which is capable of burning fuel efficiently without requiring the services of an attendant, and wherein provision is made for the mechanical or automatic ejection of ash and also for reducing the size of the larger ash particles so as to facilitate handling 20 of the ash.

A further and more specific object is to provide 25 a stoker-fired furnace including as a part thereof an ash discharge and crushing means, which is capable of being adjusted as to its operation so as to vary the rate of ash discharge and the size of the particles of ash, whereby the apparatus may be used with a wide variety of fuels 30 and under different conditions without necessitating changes in construction.

These and other objects are effected by my invention, as will be apparent from the following 35 description and claims, taken in connection with the accompanying drawings forming a part of this application, and in which—

Fig. 1 is a side elevational view showing my improvement as embodied in a household furnace; 40 Fig. 2 is a vertical sectional view taken on the line II—II of Fig. 1, and showing certain parts of the operating mechanism in elevation for the purposes of clarity; and

Fig. 3 is a vertical sectional view taken on the 45 line III—III of Fig. 2.

Referring now in detail to the construction illustrated, the reference numeral 10 indicates, in its entirety, a stoker-fired furnace of the type capable of heating a dwelling house or small apartment house, commonly referred to as a domestic stoker furnace. The furnace 10 comprises in general a combustion chamber 11, a fuel supporting surface 12 extending across the lower 50 end of the combustion chamber, a source of fuel supply 13, a means 14 for feeding fuel into the combustion chamber, an ash discharge orifice 15 extending laterally across the rear of the furnace, an ash crushing means 16, and a replaceable ash receptacle or can 17 disposed to receive

the broken-up ash as it is discharged through the orifice 15.

The combustion chamber 11 is defined by a front wall 8, a rear wall 9, and side walls 18 and 19. The fuel supporting surface 12 is composed of a stationary guide or supporting plate 20 extending entirely across the bottom of the chamber 11, and a grate structure 21 resting on the plate 20 and adapted to be reciprocated forwardly and rearwardly of the chamber to break up the fuel bed and to feed the burning fuel and resultant ash rearwardly of the furnace and to positively eject the ash laterally from the combustion chamber 11 through the orifice 15. The ash discharge orifice is defined by the lower horizontal edge of the rear wall 9, the rear end of the plate 20 and the side walls 18 and 19.

The grate structure 21 comprises a grate frame 22 and a plurality of grate bars 23 detachably mounted in the frame 22. The plate 20 is suitably supported by horizontally aligned brackets 24 extending inwardly of the furnace from the lower ends of the walls 18 and 19 defining the combustion chamber, and is provided with an opening 25 through which air for supporting combustion flows from a plenum chamber or wind box 26 arranged below the plate 20. The air is supplied to the wind box 26 by a blower 27 and such air flows upwardly into the fuel bed through suitable openings provided in the grate 25 bars 23 and through the usual spaces between the grate bars.

The grate frame 22 and grate bars 23 are constructed at their forward end in the form of a U to provide a fuel feeding opening 30 communicating with the means 14 for feeding fuel. The latter comprises an upwardly inclined duct 31 and a rotatable screw 32 extending longitudinally of the duct 31. The lower end of the duct 31 communicates with the source of fuel supply 13, here shown to be in the form of a fuel hopper, which feeds the fuel by gravity to the lower end of the duct 31 and screw 32. It will be appreciated that by rotating the screw 32 the fuel is fed upwardly through the duct 31 and through the opening 30 into the combustion chamber 11.

The fuel-feeding screw 32 may be rotated by any suitable means. For example, I have shown an electric motor 35 connected by a pulley and belt connection 36 to a suitable form of speed-reducing mechanism arranged within a housing 37 beneath the hopper 33. The mechanism in the housing 37 includes a driven shaft 38 extending horizontally out of the housing and having a bevel gear 39 suitably keyed to the outer 50 55

end thereof. The gear 39 meshes with a second bevel gear 40 which is suitably keyed to the lower end of the shaft 41 of the screw 32.

The grate frame 22 is provided with a pair of spaced downwardly extending lugs 43 which extend respectively through the opening 25 in the supporting plate 20. The supporting plate 20 is also provided with a pair of spaced downwardly extending projections 44 and aligned journal bearings 45 are provided respectively in the lower ends of these projections. The bearings receive a grate-operating shaft 46, and one end of the shaft 46 extends outside of the furnace, and an operating arm 47 is suitably keyed to the outer extension thereof. A pair of spaced operating arms 48 are suitably keyed to the shaft 46 and extend upwardly and are connected respectively at their upper ends to the downwardly extending lugs 43 of the grate by a pair of links 49. Thus, when the shaft 46 is oscillated by power applied to the arm 47, the grate frame 22, with the grate bars 23 mounted therein, is moved forwardly and rearwardly through the operating connection formed by the arms 48, links 49 and lugs 43.

The arm 47 is operatively connected to the driven shaft 38 of the speed-reducing mechanism contained in the housing 37 by means of a crank 50 suitably keyed to the extreme outer end of the shaft 38 and a connecting link 51. Thus, when the shaft 38 rotates, the rotary motion thereof is transmitted into oscillatory motion of the shaft 46 through the medium of the crank 50, link 51 and arm 47. The link 51 is pivotally connected to the arm 47 by a removable pin 52 adapted to fit any desired one of a series of holes 53 in the arm 47. Thus, the grate frame with the grate bars therein is reciprocated forwardly and rearwardly on the guide plate 20, and the amplitude of the reciprocations may be readily varied by changing the pin connection of the link 51 with the arm 47 to another one of the series of openings 53 in the arm 47.

In my copending application above referred to, of which this application is a division, I have described in detail the improved and efficient operation effected by the structure so far described. I have also described and illustrated the particular type of fuel bed maintained in the combustion chamber 11 and the detail action carried on in the fuel bed. These features are claimed in my copending application. It is believed sufficient for a clear understanding of the present invention to state that in normal operation the burning fuel bed extends entirely across the lower part of the chamber from front wall 8 to rear wall 9 and from side wall 18 to side wall 19; and that fresh fuel is fed in an upwardly inclined direction into the fuel bed and upwardly and towards the rear wall 9 by the screw 32 rotating in the upwardly inclined duct 31 which terminates at the opening 30. The fuel bed is agitated and is aided in its rearward movement by the reciprocating grate 21. As the fuel burns, ash is formed and gravitates to the lower part of the bed where it is fed rearwardly and laterally out of the orifice 15 by the grate 21.

As explained in my copending application, it is desirable that the rate of ash discharge be so regulated with respect to the rate of fuel feed, the fuel burning rate, and the ash content of the fuel, that a substantial bed of ash is always maintained adjacent the orifice. The purpose of maintaining such a bed of ash may be threefold: one, to support the rear part of the fuel bed and thereby assure the efficient combustion of the

fuel; two, to prevent the harmful infiltration of excess air into the furnace through the ash discharge orifice 15; and three, to offer a substantial resistance to the flow of air into the furnace at the rear so that air in sufficient quantities passes through the bed at the front of the furnace where the resistance is normally high due to the greater degree of coking action. This third reason is, of course, present when a coking coal is being burned.

According to the present invention, my improved form of ash crushing means 16, in conjunction with the regulatable action of the reciprocating grate 21, provides for the desired maintenance of a bed of ash adjacent the orifice, and provides for a variable rate of ash discharge from the combustion chamber to suit any type of fuel and any desired fuel burning rate. A further and important function performed by the grate and the means 16 is that they provide for the shearing or crushing of the larger particles of clinker or ash so as to assure the efficient operation of the furnace and to facilitate subsequent handling of the ash.

In the accompanying drawings, this means 16 is in the form of a vertically reciprocating plate 60 extending across the upper part of the orifice 15 and at the rear of the wall 9 to partially close the orifice 15. The plate 60 is confined to its vertical movement by guide means arranged at each end thereof and comprising vertical guide plates 61 secured respectively to the end walls 18 and 19 and spaced from the adjacent ends of the vertical rear wall 9.

The plate 60 is provided with teeth 62 on its lower forward surface which serve to feed the ash and clinker downwardly toward the orifice, and also to crush and break up the clinker. As the plate is moved downward and against the ash, the lower horizontal edge of the plate will shear or crush any clinker or large ash particles as the latter are moved out through the orifice 15 by the reciprocating grate 21.

The plate 60 is supported in its position above the rear end of the guide or supporting plate 20 and is reciprocated by means of pins 63 carried by the outer ends of arms 64 and engaging between spaced projections 65 fixed to the rear face of the plate 60. The arms 64 are fixed to an operating shaft 66 which extends outside of the furnace, as shown in Fig. 1, and is provided at its outer end with an arm 67 fixed thereto and having a retractable latch 68 at its outer end which engages any desired one of a series of notches 69 formed on the outer arcuate surface of an arm 70. The arm 70 is loosely mounted on the extreme outer end of the shaft 66 and is provided with a depending arm portion 71 which is connected at its outer end to one end of an operating link 72, the other end of the link 72 being pivotally connected to the arm 47 by a pin 73 filling a preselected one of the openings 53.

Thus, with the latch 68 engaging a preselected one of the notches 69, oscillatory motion of the arm 47 will be transmitted through the link 72, arm 70, arm 67, shaft 66, and arms 64, to the plate 60. The amplitude of reciprocation of the plate, i. e., the total distance traveled by the plate, depends upon the particular opening 53 within which the pin 73 is fitted. By changing the pin to another of the openings 53, the amplitude of reciprocations of the plate 60, i. e., the total distance traveled during each reciprocation, may be varied to suit different operating conditions. The extent or size of the ash discharge 75

orifice 15 is determined by the vertical distance between the rear edge of the plate 20 and the bottom edge of the plate 60, and in order to vary the extent or size of this orifice 15, it is only necessary to adjust the arm 10 with respect to the arm 67, which can be readily done by means of the retractable latch 68 and notches 69. By varying the amplitude of reciprocations of the plate 60, by varying the extent of size of the orifice 15, and by varying the amplitude of reciprocations of the grate 21, the rate of ash discharge and the size of the ash particles may be easily varied at will for the purposes previously explained.

What I claim and desire to secure by Letters Patent of the United States is:

15. In combustion apparatus, the combination of means defining a combustion chamber including upwardly extending front and rear wall portions; means providing a fuel supporting surface 20 face extending across the lower portion of the combustion chamber; the portion of said surface adjacent the rear wall portion terminating in the plane of said rear wall portion and being vertically spaced from the lower end thereof to provide an ash discharge orifice extending vertically through said rear wall portion; means for feeding solid fuel onto the fuel supporting surface and for discharging ash rearwardly and through the vertical orifice; an ash crushing member vertically reciprocable across the vertical orifice for crushing ash and shearing clinker formations in the ash as the ash moves through the vertical orifice, and means for reciprocating said ash crushing member, said ash crushing member and 30 the reciprocating means therefor being positioned rearwardly of the rear wall portion of said combustion chamber.

2. Apparatus according to claim 1, wherein the vertically reciprocable crushing member is provided with tooth portions which extend inwardly and overlie the adjacent end of the fuel supporting surface for engaging the ash and clinker positioned between said crushing member and the adjacent edge of the fuel supporting surface to aid in the crushing and shearing action.

3. In combustion apparatus, the combination of wall structure defining a combustion chamber; means providing a fuel supporting surface extending across the lower end of the combustion chamber; one portion of the wall structure terminating above the fuel supporting surface to define therewith a vertically-extending ash discharge orifice at one side of the chamber to permit the discharge of ash from said chamber; the fuel supporting surface including a movable portion for feeding the ash across the combustion chamber and through said vertical orifice and a stationary portion terminating in the plane of said one portion of the wall structure; a vertically reciprocable ash crushing member partially closing said vertical orifice and vertically reciprocable across said orifice toward and from the stationary portion of the fuel supporting surface and transversely of the direction of movement of ash through the orifice for crushing the ash, and means for constantly reciprocating said ash crushing member.

4. Apparatus according to claim 3, wherein means is provided for changing the position of the constantly reciprocating ash crushing member with respect to the stationary portion of the fuel supporting surface so as to vary the vertical extent of said orifice to thereby vary the rate of the ash discharge therethrough.

75 5. Apparatus according to claim 3, wherein

means is provided for varying the amplitude of the vertical reciprocations of the constantly reciprocating ash crushing member so as to vary the rate of ash discharge through the vertically-extending ash discharge orifice.

6. Apparatus according to claim 3, wherein the constantly reciprocating ash crushing member is disposed outside the combustion chamber and substantially parallel to the adjacent wall structure and the lower edge of the ash crushing member terminates above the outer edge of the stationary portion of the fuel supporting surface and teeth are provided on the combustion chamber side of the ash crushing member for feeding ash downward so that the ash can be ejected through the orifice.

7. In combustion apparatus, the combination of upright wall means defining a combustion chamber; fuel supporting means extending across the lower part of said combustion chamber and comprising a movable front portion and a stationary rear portion; the wall means at the rear of said chamber terminating immediately above the rear edge of the stationary rear portion of the fuel supporting means to define therewith a vertically-extending ash discharge orifice; means for feeding fuel onto the movable front portion of said fuel supporting means; means for feeding ash rearwardly across the stationary portion of said supporting means and through said vertical orifice; an ash crushing member extending across the upper part of the rear edge of the stationary rear portion of the orifice and movable vertically toward and away from said fuel supporting surface to engage and crush the ash as it moves through said orifice; and means for vertically reciprocating said ash crushing member, said ash crushing member and the reciprocating means therefor being positioned outside of said combustion chamber.

8. In combustion apparatus, the combination of upright wall means defining a combustion chamber; fuel supporting means extending across the lower part of said combustion chamber and comprising a movable front portion and a stationary rear portion; the wall means at the rear of said chamber terminating immediately above the rear edge of the stationary rear portion of the fuel supporting means to define therewith a vertically-extending ash discharge orifice; means for feeding fuel onto the movable front portion of said fuel supporting means; means for feeding ash rearwardly across the stationary portion of said supporting means and through said vertical orifice; a vertically reciprocable ash crushing member extending across the upper part of said orifice and including a lower ash crushing part; and means providing for vertical bodily reciprocal movement of the ash crushing member toward and away from the rear edge of the stationary rear portion of the fuel supporting surface and across said vertical orifice so that as the member moves toward said stationary rear portion the lower part of said member engages and crushes the ash as the ash moves through the vertical orifice; said last-mentioned means including an element which may be adjusted to vary the vertical extent of the discharge orifice so that the amount of ash flowing through the orifice may be varied.

9. In combustion apparatus, the combination of upright wall means defining a combustion chamber; fuel supporting means extending across the lower part of said combustion chamber and comprising a movable front portion and a sta-

tionary rear portion; the wall means at the rear of said chamber terminating immediately above the rear edge of the stationary rear portion of the fuel supporting means to define therewith a vertically-extending ash discharge orifice; means for feeding fuel onto the movable front portion of said fuel supporting means; means for feeding ash rearwardly across the stationary rear portion of said supporting means and through said vertical orifice; a vertically reciprocable ash crushing member extending across the upper part of said orifice and including a lower ash crushing part; and means providing for vertical bodily reciprocal movement of the ash crushing member toward and away from the rear edge of the stationary rear portion of the fuel supporting surface and across said vertical orifice so that as the member moves toward said stationary rear portion the lower part of said member engages and crushes the ash as the ash moves through the vertical orifice; said last-mentioned means including means for varying the amplitude of the vertical reciprocal movement.

10. In combustion apparatus, the combination of upright wall means defining a combustion chamber; fuel supporting means extending across the lower part of said combustion chamber and comprising a movable front portion and a stationary rear portion; the wall means at the rear of said chamber terminating immediately above the rear edge of the stationary rear portion of the fuel supporting means to define therewith a vertically-extending ash discharge orifice; means for feeding fuel onto the movable front portion of said fuel supporting means; means for feeding ash rearwardly across the stationary rear portion of said supporting means and through said vertical orifice; a vertically-reciprocable ash crushing member extending across the upper part of said orifice and including a lower ash crushing part; and means providing for vertical bodily reciprocal movement of the ash crushing member toward and away from the rear edge of the stationary rear portion of the fuel supporting surface and across said vertical orifice so that as the member moves toward said stationary rear portion the lower part of said member engages and crushes the ash as the ash moves through the vertical orifice; said last-mentioned means including an element which may be adjusted to vary the vertical extent of the discharge orifice so that the amount of ash flowing through the orifice may be varied, and means for varying the amplitude of the vertical reciprocal movement of said member.

11. In combustion apparatus, the combination of upright walls defining a combustion chamber; means providing a fuel supporting surface extending across the lower part of said combustion chamber; one of said walls terminating above the adjacent part of said surface to provide an ash discharge orifice at one side of said chamber; means for feeding fuel onto said surface and for moving ash through said orifice; upright guide means adjacent said one wall and at the walls defining each end of said orifice; an ash crushing plate extending lengthwise across said orifice from end to end thereof and having its end parts supported for upward and downward movement in said guide means and having a lower surface for engaging and crushing the ash; a shaft adjacent said plate and extending in the direction of length of the plate and being supported for oscillatory movement; power transmitting

means connecting said plate and said shaft for supporting said plate with its lower surface above the level of the fuel supporting surface when the shaft is stationary and for reciprocating said plate upward and downward when said shaft is oscillated; and means for imparting oscillatory movement to said shaft.

12. In combustion apparatus, the combination of upright walls defining a combustion chamber; means providing a fuel supporting surface extending across the lower part of said combustion chamber; one of said walls terminating above the adjacent part of said surface to provide an ash discharge orifice at one side of said chamber; means for feeding fuel onto said surface and for moving ash through said orifice; upright guide means adjacent said one wall and at the walls defining each end of said orifice; an ash crushing plate extending lengthwise across said orifice from end to end thereof and having its end parts supported for upward and downward movement in said guide means and having a lower surface for engaging and crushing the ash; a shaft adjacent said plate and extending in the direction of length of the plate and being supported for oscillatory movement; power transmitting means connecting said plate and said shaft for supporting said plate with its lower surface above the level of the fuel supporting surface when the shaft is stationary and for reciprocating said plate upward and downward when said shaft is oscillated; and means for oscillating said shaft including a first operating arm loosely journaled on said shaft and having a toothed sector part, a second arm fixed at one end to said shaft adjacent said first arm and having a retractable latch device at its outer end engaging one of the teeth of said sector, and means for oscillating said first arm.

13. In combustion apparatus, the combination of upright walls defining a combustion chamber; means providing a fuel supporting surface extending across the lower part of said combustion chamber; one of said walls terminating above the adjacent part of said surface to provide an ash discharge orifice at one side of said chamber; means for feeding fuel onto said surface and for moving ash through said orifice; upright guide means adjacent said one wall and at the walls defining each end of said orifice; an ash crushing plate extending lengthwise across said orifice from end to end thereof and having its end parts supported for upward and downward movement in said guide means and having a lower surface for engaging and crushing the ash; a shaft adjacent said plate and extending in the direction of length of the plate and being supported for oscillatory movement; power transmitting means connecting said plate and said shaft for supporting said plate with its lower surface above the level of the fuel supporting surface when the shaft is stationary and for reciprocating said plate upward and downward when said shaft is oscillated; and means for oscillating said shaft including a first operating arm loosely journaled on said shaft and having a toothed sector part, a second arm fixed at one end to said shaft adjacent said first arm and having a retractable latch device at its outer end engaging one of the teeth of said sector, and means for oscillating said first arm and including means for varying the amplitude of such oscillations.

DONALD J. MOSSHART.
